UNITED STATES PATENT OFFICE.

HENRY RITHNER, OF WELLSBURG, WEST VIRGINIA, ASSIGNOR TO CRESCENT GLASS COMPANY, OF WELLSBURG, WEST VIRGINIA, A CORPORATION OF WEST VIRGINIA.

HOOD FOR ELECTRIC LAMPS.

1,086,787.

Specification of Letters Patent. Patented Feb. 10, 1914.

Application filed April 7, 1913. Serial No. 759,311.

To all whom it may concern:

Be it known that I, HENRY RITHNER, a citizen of the United States of America, and resident of Wellsburg, county of Brooke, 5 and State of West Virginia, have invented certain new and useful Improvements in Hoods for Electric Lamps, of which the following is a specification.

This invention relates broadly to hoods 10 for electric lamps, and specifically to a hood and attaching means therefor.

The primary object of the invention is to provide a transparent lamp-inclosing hood of the general type commonly employed in 15 electric signs, having novel and improved means for attachment whereby it is held in fixed relation to the lamp and whereby the latter is, at the same time, yieldingly engaged, permitting the lamp to freely expand 20 and contract.

A further object is to provide a glass hood of the character mentioned which may be formed by pressing, as distinguished from hoods which require that they be blown, thus 25 insuring a uniformity of thickness, which is impossible of attainment in hoods formed by blowing.

Further important objects will in part be made apparent and in part pointed out here- 30 inafter.

The invention resides in the features of construction, arrangement of parts and combinations of elements which will hereinafter be exemplified, reference being had to the 35 accompanying drawings, forming a part of this specification, in which—

Figure 1 is a side elevation of the invention; Fig. 2 is a longitudinal section of the same; Fig. 3 is a side elevation of the hood; 40 Fig. 4 is a cross section of the hood-supporting ring or collar; and Fig. 5 is a bottom plan view of the same.

Referring to said drawings, in which like designating characters distinguish like parts throughout the several views—1 indicates an electric lamp bulb which is seated in a lamp socket 2, as ordinarily. Loosely encircling the neck of the bulb 1 and seated against the outer end of the socket 2 is a 45 ring or collar 3, preferably formed of sheet-metal, having an annular outwardly directed flange 4 which has screw-threads 4^a formed therein for receiving the external threads 5 formed about the mouth of a glass

hood 6 which wholly incloses the lamp bulb 55 1. Said hood is threaded within the flange 4 of the ring or collar 3 and is thus rigidly supported with respect to said collar. Constituting means whereby said collar is yieldingly supported is a plurality of spring fingers 7 formed integral with said collar and projecting from the inner periphery thereof. Said fingers normally lie in parallel alinement with the longitudinal axis of the collar, or at substantially right angles to the plane of the body portion of said collar, as shown in Fig. 4, and are adapted to yieldingly seat upon the bulb adjacent to that portion thereof having the smallest diameter, and, when so seated, to be pressed 60 slightly outward in an inclined direction toward that portion of the bulb having the greatest diameter, as shown in Fig. 2. Said fingers are preferably weakened adjacent to their points of junction with the collar by 65 undercutting at opposite sides to lessen the width, as shown at 7^a, so that flexure resulting from pressure thereon will occur primarily adjacent to the collar, causing said fingers to lie substantially flat upon the surface of the bulb, as shown in Fig. 2.

The collar is placed in encircling relation to the smaller end of the bulb prior to the mounting of the same in the socket 2. As the bulb is threaded into the socket, the fingers are gradually flexed outward from their normal positions in parallel alinement with the axis of the bulb to inclined positions, substantially as shown in Fig. 2. A yielding support is thus constituted for the hood 70 6 which is then threaded within the flange 4 of the collar.

Owing to the fact that the bulb is engaged only by the yielding spring fingers, expansion and contraction of the bulb is readily 75 permitted without undue strain being placed on the latter.

A plurality of suitable holes or apertures, as 8, are provided in the body portion of the collar for permitting of the ready escape 80 of heat generated in the lamp. The said body portion serves as a reflector whereby inwardly directed light rays, which are permitted by the usual or common forms of hood-supports to escape through the mouth 85 of the hood, and to be thus wasted, are directed back and out through the hood.

As is apparent, the hood 6 may be made

in a press-mold as well as in a blow-mold, in view of the fact that its interior is plain and smooth, offering no hindrance to the withdrawal of the plunger of such press-mold. This is an advantageous feature, particularly because the walls of hoods formed by pressing may be made of uniform thickness throughout, not being affected by differences of temperature in different parts of the mold, as in the process of manufacture in blow-molds.

Having thus described my invention, what I claim as new, and desire to secure by Letters Patent, is—

- 15 1. The combination with a lamp bulb, of a hood inclosing said bulb, and hood-supporting means comprising a metal bulb-encircling collar having an outwardly directed peripheral flange within which said hood is adapted to seat, and having integral resilient fingers for seating upon said bulb.
- 20 2. The combination with a lamp bulb, of a hood inclosing said bulb, and hood-supporting means comprising a metal bulb-encircling collar having an outwardly directed peripheral flange within which said hood is adapted to seat, and having integral resilient fingers for seating upon said bulb, said fingers normally lying in planes parallel to the axis of the bulb.
- 25 3. The combination with a lamp bulb, of a hood inclosing said bulb, and hood-supporting means comprising a metal bulb-encircling collar having an outwardly directed peripheral flange within which said hood is adapted to seat, and having integral yielding fingers adapted to seat substantially flatwise upon the surface of said bulb.
- 30 4. The combination with a lamp bulb, of a hood inclosing said bulb, and hood-supporting means comprising a metal bulb-encircling collar having an outwardly directed peripheral flange for the reception of the open end of said hood, and integral fingers formed on the inner periphery of said collar and adapted to yieldingly seat upon the surface of the bulb, said fingers normally occupying planes substantially parallel to the axis of the bulb and being adapted to be forced outward to positions substantially parallel to the surface engaged thereby.
- 35 5. The combination with a lamp bulb, of an inclosing hood for said bulb, and a hood-supporting member, said member comprising a sheet-metal collar disposed in encircling relation to the neck portion of said bulb and having a plurality of resilient fingers projecting outward from its inner periphery in a direction substantially at right angles thereto for yieldingly seating upon the surface of said bulb behind the point of greatest diameter of the latter, and a pe-

ripheral flange formed on said collar and within which said hood is adapted to seat.

6. The combination with a lamp bulb, of a hood for inclosing said bulb, said hood being threaded exteriorly at a point adjacent to the mouth thereof, and a hood-supporting member, said member comprising a collar for loosely encircling the neck portion of said bulb and having a peripheral threaded flange for receiving the threaded portion of said hood, and a plurality of resilient fingers formed on the inner periphery of said collar and adapted to yieldingly seat upon the surface of said bulb.

7. The combination with a lamp bulb, of a bulb-inclosing hood, and a hood-supporting member comprising a collar for loosely encircling said bulb and constituting a reflector for light rays, an outer peripheral flange formed on said collar and in which said hood is adapted to firmly seat, and resilient fingers formed on the inner periphery of said collar and adapted to yieldingly seat upon the surface of said bulb.

8. The combination with a lamp bulb, of a bulb-inclosing hood, and a hood-supporting member comprising a collar for loosely encircling said bulb and constituting a reflector for light rays, said collar having heat-outlet openings therein, an outer peripheral flange formed on said collar and in which said hood is adapted to firmly seat, and resilient fingers formed on the inner periphery of said collar and adapted to yieldingly seat upon the surface of said bulb.

9. The combination with a lamp bulb, of a hood inclosing said bulb, and hood-supporting means comprising a metal bulb-encircling collar having an outwardly directed peripheral flange within which said hood is adapted to seat, and having integral resilient fingers for seating upon said bulb, said fingers being weakened by undercutting at points adjacent to their points of junction with said collar.

10. The combination with a lamp bulb, of a hood having a smooth unbroken interior surface, means for supporting said hood comprising a collar loosely encircling the neck portion of said bulb and having an outer peripheral flange adapted to firmly seat said hood, and resilient fingers formed on said collar for seating upon the surface of said bulb.

In testimony whereof, I affix my signature in presence of two subscribing witnesses.

HENRY RITHNER.
